UNITED STATES PATENT OFFICE.

HOMER S. DRIESSLEIN, OF FORT DODGE, IOWA.

SAVINGS DEVICE.

1,299,562.

Specification of Letters Patent.

Patented Apr. 8, 1919.

Application filed February 15, 1917. Serial No. 143,910.

To all whom it may concern:

Be it known that I, HOMER S. DRIESSLEIN, a citizen of the United States, and resident of Fort Dodge, in the county of Webster and State of Iowa, have invented a certain new and useful Savings Device, of which the following is a specification.

The object of my invention is to provide a device for encouraging savings, of simple and inexpensive construction.

More particularly it is my object to provide a book having a plurality of sheets substantially bound together, and detachably supported in a cover, said sheets being provided near one end with certain indicating characters for encouraging savings, and with a plurality of parts adapted to be removed from the sheet by tearing on perforated lines, said parts having indicating characters representing amounts, and annual income on said amounts.

With these and other objects in view, my invention consists in the construction, arrangement and combination of the various parts of the device, whereby the objects contemplated are attained, as hereinafter more fully set forth, pointed out in my claim, and illustrated in the accompanying drawings, in which:

Figure 1 shows a side elevation of a book embodying my invention.

Fig. 2 shows a plan view of the first sheet of the book.

Fig. 3 shows a plan view of a portion of another sheet.

Fig. 4 shows a similar view of a portion of the third sheet.

Fig. 5 shows a similar view of a portion of a fourth sheet.

Fig. 6 shows a similar view of a portion of the second sheet, and

Fig. 7 shows an inside of the cover of the book illustrating the instructions, which are given with each book issued.

My improved device, as illustrated in the accompanying drawings, consists of a book cover indicated by the reference character 10, adapted to be opened readily and having on its interior a transverse strip or pocket member 11, terminating short of the hinged back of the book. In the cover 10, I mount a plurality of sheets 12, bound together by clips or the like 13.

Secured to the back sheet is a strip of pasteboard or the like 14, adapted to be slipped between the pocket member 11 and

the back cover member of the book 10 for holding the sheets in position.

Before explaining the actual construction of my device, I will explain the general purpose for which it is intended.

It is my object to provide a booklet of the kind mentioned adapted to encourage savings by presenting to the user in a very vivid way the value of small amounts which are frequently misspent or wasted.

For this purpose, I place at the top of each sheet indicating characters such as the words "Annual income on \$20.00 spent unnecessarily," indicated in Fig. 2, by the reference character 15.

I preferably also place on the upper portion of each sheet the word "From" followed by a blank, and spaced therefrom the word "To" followed by a blank.

At the upper part of each sheet but in the space below the place for the dates, which indicate the period of time covered by a given sheet, I place an indicating character 16, which in the form of device here shown indicates the number of the sheet and also the actual amount spent in dollars unnecessarily from the time the book was issued up to the time that the sheet is used up.

In Fig. 2 I have shown the first sheet of the book with the phrase "My income. Is this the way to spend it?" Adjacent to the numeral 16 in Fig. 6 near the upper portion of sheet 2 is the phrase "I'll never pay any income tax this way." Each sheet is designed to receive some similar catchy phrase as indicated by the phrases used with the sample sheets 5, 30 and 50 represented in Figs. 3, 4, and 5 respectively.

Below the figure and the catchy phrases just described each sheet is divided into a plurality of squares or other regular coupons 17 by means of parallel longitudinal and transverse rows of perforations 18. On each square or coupon so formed are placed indicating characters representing the different amounts of money, as for instance, five cents. The number of such squares or coupons formed in each sheet should be such that the total amount represented thereby is equal to an amount proportionate to the amount of money represented as spent unnecessarily by the entire book. Referring to Fig. 5 it will be seen that the entire book in the form illustrated represents an amount spent, which would be the annual income of one thousand dollars and assuming that the in-

- come would be paid at the rate of five per cent. the book represents fifty dollars actual cash as spent unnecessarily. In this illustration the total amount of the coupons formed 5 on each sheet should, therefore, be one dollar or one-fiftieth of the total amount represented by the entire book. The form shown is very desirable as the numeral 16 may, therefore, both illustrate the amount of 10 money, which has been spent when all the coupons have been torn off from any given sheet and the sheets thereabove and also may indicate the number of sheets from which the coupons have been torn off.
- 15 This book is furnished to the user with instructions which may be verbal or printed on the inside of the cover so that whenever a small amount of money is spent unnecessarily enough of the squares 17 should be 20 torn from the sheets of the book to equal the amount so spent.
- In Fig. 3, I have shown the fifth sheet on which the catchy phrase is "This one slipped away," and at the top of the sheet 25 is a statement "Annual income on one hundred dollars spent unnecessarily."
- In Fig. 4, I have shown the thirtieth sheet bearing at the top the statement "Annual income on six hundred dollars spent unnecessarily," and bearing the catchy phrase, 30 "A month's rent 'gone up in smoke.'"
- Fig. 5 shows sheet fifty with indicating characters carrying out the same plan.
- It will be seen that whenever a small 35 amount is spent, the user of the book can simply tear out the proper number of squares 17, and will then retain and record such unnecessary expenditures without writing them down.
- 40 The general plan is designed for use by

banks or other institutions who desire to encourage the habit of saving, and as a correlate thereto, the habit of depositing money in the bank.

It will be understood that the indicating 45 characters may be changed, but I prefer characters for conveying the substantial information shown in my illustration, and it is my intention to cover by the claims of my patent any modified forms of devices, which 50 may be reasonably included within the scope of my claim.

I claim as my invention:

In a device of the class described for indicating money spent foolishly, the combination of a cover having an interior retaining loop, with a plurality of bound sheets arranged in a book, a member secured to said sheets arranged to co-operate with said loop for holding the sheets in the cover, said 60 sheets having at their upper ends numerals arranged in consecutive order on the various sheets, the words "From" and "To" followed by blanks for dates and a statement that said numeral represents interest on a 65 certain sum unnecessarily spent, and having below said numerals spaced longitudinal and transverse rows of perforations, whereby the lower part of the sheet may be readily detached in small regularly shaped sections, 70 each section having indicating characters thereon, representing such amounts of money that the total amount represented by all the sections on a given sheet and all the sheets thereabove will equal an amount represented by the number at the top of said sheet.

Des Moines, Iowa, February 1, 1917.

HOMER S. DRIESLEIN.
